(57) **CLAIM**

The ornamental design for a chair mountable bag, as shown and described.

DESCRIPTION

FIG. 1 is a front perspective view of a chair mountable bag showing my new design;

FIG. 2 is a left side view of a chair mountable bag;

FIG. 3 is a front view of a chair mountable bag;

FIG. 4 is a bottom view of a chair mountable bag;

FIG. 5 is a back view of a chair mountable bag;

FIG. 6 is a top view of a chair mountable bag; and,

FIG. 7 is a perspective view of a chair mountable bag as mounted on the back of a lounge chair.

Right side view not shown are mirror images of left side view. The broken lines showing a lounge chair are for the purposes of illustrating environment and form no part of the claimed design.

The smaller spaced broken lines showing stitching are part of the claim design.
